(57) **CLAIM**

The ornamental design for a light fixture, as shown and described.

DESCRIPTION

FIG. 1 is a perspective view from below of a light fixture in accordance with my design;

FIG. 2 is a reduced top plan view of the light fixture in accordance with my design;

FIG. 3 is a reduced bottom plan view of the light fixture in accordance with my design; and,

FIG. 4 is a side elevation view of the light fixture in accordance with my design, all sides being mirror images thereof.

The broken lines showing environmental structure are for illustrative purposes and form no part of the claimed design.
